ENGINE

Harold H. Timian, Detroit, Mich., assignor to
 Continental Motors Corporation, Detroit, Mich.,
 a corporation of Virginia

Application June 22, 1931, Serial No. 545,874

15 Claims. (Cl. 123—52)

My invention relates to internal combustion engines and more particularly to an intake manifold structure adapted for use therewith for distributing the fuel mixture to the engine cylinders.

In many instances it is found desirable to employ down-draft fuel mixture forming devices or carburetors which will produce improved operating results with respect to fuel distribution. A down-draft carburetor has many other apparent advantages over the up-draft carburetor but heretofore difficulty has been experienced in properly distributing the wet fuel accumulations tending to collect within the manifold structure.

An object of my present invention is to construct an internal combustion engine employing a carburetor or fuel mixture forming device of the down-draft type and having generally improved operating characteristics.

Another object of my invention is to construct a manifold structure adapted for cooperative assembly with a down-draft carburetor and in which means are provided for accurately and uniformly distributing the fuel mixture as desired for providing an engine of improved operating characteristics.

A further object of my invention is to provide means for distributing the fuel mixture to the engine cylinders employing a carburetor of the down-draft type by providing a manifold structure adapted for cooperative assembly with a carburetor of the down-draft type and in which means are provided for inducing a stratified fuel mixture flow through the manifold branches for conducting a fuel mixture through the engine in such a way as to uniformly distribute the fuel mixture to the engine cylinders.

A more detailed understanding of my invention may be had by referring to the accompanying drawings illustrating preferred embodiments of my invention and in which:

Fig. 1 is a fragmentary side elevational view of an internal combustion engine illustrating a manifold structure assembled therewith and constructed in accordance with my invention.

Fig. 2 is a vertical sectional view of my improved intake manifold structure and taken on the line 2—2 of Fig. 4.

Fig. 3 is a horizontal section taken substantially on the line 3—3 of Fig. 4.

Fig. 4 is a transverse vertical sectional view of my improved structure taken substantially on the line 4—4 of Fig. 2.

Fig. 5 is a transverse sectional view through one of the manifold branches diagrammatically il-

lustrating how the fuel mixture is stratified in operation.

Fig. 6 is a plan view of the construction illustrated in Fig. 1.

Fig. 7 is a horizontal sectional view illustrating a modified construction in which the manifold branch is provided with a partition extending longitudinally thereof for dividing the fuel mixture flow.

Fig. 8 is a detail sectional view taken on the line 8—8 of Fig. 7.

Fig. 9 is a horizontal sectional view illustrating a further modified construction in which the groove in said manifold structure is extended for a greater distance than illustrated in Figures 1 and 3.

Fig. 10 is a horizontal sectional view of a further modified construction of a manifold employing a "kick-back" in the port runner, and

Fig. 11 is a horizontal sectional view of a further modified construction illustrating a divided manifold branch.

The intake manifold structure A illustrated in Figures 1 to 6 inclusive is adapted to be assembled with an internal combustion engine which in general consists of an engine cylinder block 10 having an intake passage 11 communicating with engine intake ports (not shown). This manifold structure A is preferably arranged for association with a conventional engine of the multiple cylinder type and consists of a primary fuel mixture conducting portion 12 communicating with a fuel mixture forming device or carburetor 13. The manifold structure also includes a fuel mixture distributing chamber 14 and the fuel mixture conducting portion 12 extends downwardly in communication with said distributing chamber 14. Manifold branches 15 are connected in open communication with the distributing chamber and extend laterally and upwardly from said chamber as at 16. Preferably these branches or runners are sloped upwardly for only a portion of their length as illustrated in Fig. 2.

The manifold structure is constructed in such a way as to provide what I term a settling basin 17 which is positioned in the floor of the distributing chamber 14 opposite to the outlet of said fuel mixture conducting portion 12. The sloping portion of said manifold branches or runners are each provided with a groove 18 in the floor thereof these grooves opening into the settling basin 17 and terminating slightly beyond the termination of said sloping portion of the manifold branches. Preferably these grooves 18 are located substantially in the center of the branches as il-

lustrated in Fig. 3 and are relatively shallow in order to facilitate movement of the wet fuel by action of the fuel mixture movement.

The purpose for which these grooves were provided is to induce a stratified fuel flow in the manifold branches 15. In a down-draft fuel conducting manifold structure as illustrated in the accompanying drawings there is a tendency of the wet fuel to accumulate along the floor of the manifold structure and in the construction shown in the illustrated embodiment of my invention wet fuel tends to accumulate in the settling basin 17. In the operation of the engine the fuel mixture is drawn by suction through the manifold branches and the wet fuel is caused to flow through said upwardly inclined branch portions in response to the pull or forces exerted by the moving fuel mixture and the groove located in the floor thereof receives the wet fuel precipitates and confines this fuel flow in a prescribed path toward the engine cylinders. Thus the wet fuel is caused to flow in a desired strata substantially along the center line of the manifold branch. On increasing the speed of the engine any wet fuel flowing along the groove 18 is whipped off adjacent the end of the groove remote from the distributing chamber into the zone lying in the vicinity of the axis of said manifold branch, and thus the groove induces the stratified fuel mixture flow in the manifold branch at relatively high engine speeds as well as at relatively low engine speeds. Fig. 5 diagrammatically illustrates the stratification within the manifold branch produced by the construction herein illustrated. It will be noted that the fuel mixture between the planes indicated by the dotted lines 19 is relatively more dense than the fuel mixture to the other side of these planes. It will be noted that the outer limits of the dense strata of fuel mixture very closely approximates a plane extending longitudinally of the manifold branch and containing the side walls of the groove 18.

As shown in Figures 2 to 4 inclusive the exhaust gases are conducted in proximity with the fuel distributing chamber 14 and the floor of the settling basin 17. The structure herein illustrated provides a heating jacket 20 surrounding the fuel mixture distributing chamber 14 and a portion of the exhaust gases is permitted to flow through the jacket 20 since this jacket is communicated as at 21 with the exhaust gas conducting passage 22. A port 23 provides an outlet for the jacket 20 and the relative sizes of these ports 21 and 23 regulate the amount of exhaust gases permitted to flow through the heating jacket 20.

Fig. 7 illustrates a modified construction in which the manifold branches 25 are provided with a partition wall 26 extending substantially the entire length of the manifold branch. Preferably this partition wall terminates at a point adjacent the end of the shallow groove 18 remote from the fuel mixture distributing chamber 14 and is constructed to abut the partition wall 27 dividing the cylinder intake passage into separate intake chambers 28 each intake chamber adapted for association with a single cylinder intake port.

Fig. 9 illustrates another modified construction in which the relatively shallow wet fuel conducting groove 18' is extended to a point adjacent the outlet of the manifold branch 15'. In this construction the manifold branch may be arranged to thus deliver the fuel mixture to a cylinder intake chamber cooperatively associated with Siamese ports or said intake chamber may be constructed similar to the construction illustrated in Fig. 7

in which the intake chamber or passage is divided by a partition wall 27' illustrated by the dotted lines. Fig. 10 illustrates a modified construction having a fuel mixture distributing chamber grooves and other manifold portions constructed substantially similar to that shown in Figures 2 and 3. However, in this construction the port runner portion 40 of the manifold structures is not positioned substantially at right angles to the lateral runner 41 as in the case of the previously described constructions but is inclined therewith at an angle of more than 90° and is provided with a kick-back portion 42 which acts upon said stratified fuel flow to discharge the same through the outlet 43 in such a way as to uniformly distribute the fuel mixture to the respective engine cylinders.

In Fig. 11 I have provided a manifold structure consisting of a lateral runner 45 communicating with the fuel distributing chamber 14, said lateral runner communicating with a plurality of port runners 46. The construction herein illustrated provides a manifold portion 47 which acts to divide the fuel mixture flow and distribute the same into said port runner portions. Preferably the relatively shallow wet fuel conducting groove 18^a is extended to a point adjacent to said fuel mixture dividing means or split 47.

It will be apparent to those skilled in the art to which my invention pertains that various modifications and changes may be made therein without departing from the spirit of my invention or from the scope of the appended claims.

What I claim as my invention is:

1. In an engine having a fuel mixture forming device, an intake manifold structure having a fuel mixture distributing chamber, a primary fuel mixture conducting portion communicating with the fuel mixture forming device and extending downwardly to said distributing chamber, and manifold runner portions extending laterally and upwardly from said chamber and constructed to induce a stratified fuel flow therein along the bottom wall thereof at relatively low engine speeds and adjacent the central longitudinal axial plane through said runner portion at relatively high engine speeds.

2. In an engine having a fuel mixture forming device, an intake manifold structure having a fuel mixture distributing chamber, a primary fuel mixture conducting portion communicating with the fuel mixture forming device and extending downwardly to said distributing chamber, and manifold branches consisting of lateral and port runner portions and communicating with said fuel mixture distributing chamber, said lateral and port runner portions positioned at an angle to each other and connected by a bend, said lateral runner portion provided with a wet fuel conducting groove in the floor thereof extending from the distributing chamber to a point beyond the bend for inducing a stratified directional fuel flow in said runner portions.

3. In an engine having a fuel mixture forming device, an intake manifold structure having a fuel mixture distributing chamber provided with a substantially flat bottom portion, a primary fuel mixture conducting portion communicating with the fuel mixture forming device and extending downwardly to said distributing chamber whereby the fuel mixture carried thereby is impinged on said flat bottom portion, and laterally extending manifold runner portions communicating with said fuel mixture distribut-

ing chamber and provided with wet fuel conducting relatively shallow grooves communicating with the bottom portion of said distributing chamber for inducing a stratified fuel flow therein during engine operation.

4. In an engine having a fuel mixture forming device, an intake manifold structure having a fuel mixture distributing chamber provided with a substantially flat bottom portion, a primary fuel mixture conducting portion communicating with the fuel mixture forming device and extending downwardly to said distributing chamber whereby the fuel mixture carried thereby is impinged on said flat bottom portion, and manifold runner portions extending laterally and upwardly from said chamber and provided with wet fuel conducting relatively shallow grooves in the floor of said portions communicating with the bottom portion of said distributing chamber and extended laterally and upwardly to induce a stratified fuel flow therein.

5. A manifold structure including a distributing chamber and a plurality of fuel conducting portions communicating with the cylinders of a multi-cylinder internal combustion engine and with said distributing chamber, and a primary fuel conducting portion extending downwardly to said distributing chamber, means within said conducting portions for dividing said fuel flow at a point spaced from said distributing chamber an amount sufficient to permit the fluid to attain equilibrium prior to being acted upon by said dividing means, and a groove intermediate said distributing chamber and said fuel flow dividing means for inducing a stratified wet fuel flow, said groove terminating ahead of the said fuel flow dividing means.

6. In a multi-cylinder engine having a fuel mixture forming device, an intake manifold structure having a fuel mixture distributing chamber, a primary fuel mixture conducting portion communicating with the fuel mixture forming device and extending downwardly to said distributing chamber, and laterally extending manifold runner portions communicating with said fuel mixture distributing chamber, said lateral runner portions provided with means acting on the wet fuel flowing along a wall of the manifold structure and inducing a stratified directional fuel flow toward the engine cylinders, whereby to facilitate distribution of the fuel to the engine cylinders during engine operation.

7. In a multi-cylinder engine having a fuel mixture forming device, an intake manifold structure having a fuel mixture distributing chamber, a primary fuel mixture conducting portion communicating with the fuel mixture forming device and extending downwardly to said distributing chamber, and manifold runner portions extending laterally and upwardly from said chamber and provided with means inducing a stratified directional fuel flow therein toward the engine cylinders, whereby to facilitate distribution of the fuel to the engine cylinders during engine operation.

8. In a multi-cylinder engine having a fuel mixture forming device, an intake manifold structure having a fuel mixture distributing chamber, a primary fuel mixture conducting portion communicating with the fuel mixture forming device and extending downwardly to said distributing chamber, and laterally extending manifold runner portions communicating with said fuel mixture distributing chamber, said lateral runner portions provided with means acting on the wet

fuel flowing along a wall thereof for inducing a stratified directional fuel flow therein toward the engine cylinders throughout a range of engine speeds whereby to facilitate distribution of the fuel and fuel mixture to the engine cylinders during engine operation.

9. In a multi-cylinder engine having a fuel mixture forming device, an intake manifold structure having a fuel mixture distributing chamber, a primary fuel mixture conducting portion communicating with the fuel mixture forming device and extending downwardly to said distributing chamber, and laterally extending manifold runner portions for distributing fuel mixture to the engine cylinders and chambers, said runner portions provided with fuel conducting grooves of relatively shallow depth in the floor of the runner portions to induce a stratified directional fuel flow therein toward the engine cylinders whereby to facilitate distribution of said fuel to the engine cylinders.

10. In an engine having a fuel mixture forming device, an intake manifold structure having a fuel mixture distributing chamber, a primary fuel mixture conducting portion communicating with the fuel mixture forming device and extending downwardly to said distributing chamber, and manifold branches consisting of lateral and port runner portions and communicating with said fuel mixture distributing chamber, said lateral runner portion provided with a wet fuel conducting groove of relatively shallow depth in the floor thereof to induce a stratified directional fuel flow therein toward the engine cylinders whereby to facilitate distribution of said fuel to the engine cylinders.

11. In an engine having a fuel mixture forming device, an intake manifold structure having a fuel mixture distributing chamber, a primary fuel mixture conducting portion communicating with the fuel mixture forming device and extending downwardly to said distributing chamber, and manifold branches consisting of lateral and port runner portions and communicating with said fuel mixture distributing chamber, said lateral and port runner portions provided with a continuous relatively shallow wet fuel conducting groove in the floor thereof whereby to induce a stratified fuel flow therein and to impart directional flow thereto toward the engine cylinders.

12. In an engine having a fuel mixture forming device, an intake manifold structure having a fuel mixture distributing chamber, a primary fuel mixture conducting portion communicating with the fuel mixture forming device and extending downwardly to said distributing chamber, manifold branches consisting of lateral and port runner portions and communicating with said fuel mixture distributing chamber, and fuel distributing means within said runner portions extending longitudinally thereof from said distributing chamber towards the engine cylinders, said means acting on the wet fuel flowing along the walls of said manifold structure for inducing a stratified directional fuel flow in said runner portions towards the engine cylinders during engine operation, whereby to facilitate distribution of said fuel to the engine cylinders.

13. In a multi-cylinder engine having a fuel mixture forming device, an intake manifold structure having a fuel mixture distributing chamber, a primary fuel mixture conducting portion communicating with the fuel mixture forming device and extending downwardly to said distributing chamber, manifold branches

consisting of lateral and port runner portions and communicating with said fuel mixture distributing chamber, said manifold structure having an outlet positioned at a higher level than said distributing chamber, and wet fuel conducting means extending longitudinally within said lateral runner portion for inducing a stratified directional fuel flow therein towards the engine cylinders, whereby to facilitate the distribution of the fuel to the engine cylinders during engine operation.

14. In a multi-cylinder engine having a fuel mixture forming device, an intake manifold structure having a fuel mixture distributing chamber, a primary fuel mixture conducting portion communicating with the fuel mixture forming device and extending downwardly to said distributing chamber, said manifold structure having an outlet positioned at a higher level than said distributing chamber, and manifold runner portions extending laterally and upwardly from said chamber and provided with means within said runner portions for inducing a stratified

directional fuel flow therein towards the engine cylinders over a range of engine speeds, whereby to facilitate the uniform distribution of the fuel to the engine cylinders during engine operation at varying engine loadings.

15. In an engine having a fuel mixture forming device, an intake manifold structure having a fuel mixture distributing chamber, a primary fuel mixture conducting portion communicating with the fuel mixture forming device and extending downwardly to said distributing chamber, said manifold structure having an outlet positioned at a higher level than said distributing chamber, and manifold branches including a lateral runner portion having a portion adjacent to and communicating with the fuel mixture distributing chamber inclined upwardly and provided with a wet fuel conducting groove whereby to induce a stratified directional fuel flow in said runner portion towards the engine cylinders during engine operation.

HAROLD H. TIMIAN.
